UNITED STATES PATENT OFFICE.

JACOB AIZENMAN, OF BROOKLYN, NEW YORK.

COMBINED CURTAIN AND DRAPERY.

Application filed September 3, 1924. Serial No. 735,593.

This invention relates in general to hangings and more particularly to a combined curtain and drapery designed for use on windows or the like.

5 The object of my invention is the provision of a combined curtain and drapery wherein the curtain and the drapery are constituted of the different materials best suited to their respective purposes and yet are so 10 organized that both the curtain and the drapery have a pleasing and a graceful hang and the two produce a rich decorative effect.

A further object of my invention is the provision of a combined curtain and drapery 15 of the character specified and having the advantages and capacities hereinabove mentioned and which is adapted to be made up easily and comparatively inexpensively, the maximum of drapery effect being possible 20 with economy in the use of materials.

Other objects and advantages reside in the certain novel features of the construction, arrangement and combination and particulars, which will be hereinafter more fully described and particularly pointed out in the 25 appended claim, reference being had to the accompanying drawings forming a part of this specification and in which:

Fig. 1 is a view in elevation showing one 30 embodiment of my invention.

Fig. 2 is a view thereof in vertical section taken approximately on line 2—2 of Fig. 1.

Fig. 3 is a view in horizontal section taken on line 3—3 of Fig. 1.

35 Fig. 4 is a view similar to Fig. 3, but showing a slightly different form of the invention.

Fig. 5 is a view in elevation of another embodiment of the invention.

Fig. 6 is a view in vertical section of line 40 6—6 of Fig. 5, and

Fig. 7 is a view in horizontal section on line 7—7 of Fig. 5.

Referring to the drawings, wherein for the sake of illustration is shown the preferred em- 45 bodiments of the invention, and more particu-

larly to Figs. 1 to 3, inclusive, the numeral 10 designates a main curtain panel which may be made of lace material or silk lace material. In fact, the curtain may be 50 made of any ordinary curtain material and the usual characteristics of such materials are that they are of light-weight and are more or less reticulated or porous so as not to shut out light and air. At its lower end the main panel 10 may be provided with a fringe 11.

Obviously, one or more panels 10 may be pro-

vided for the window, or the like, to which the hanging is to be applied.

An overdrape designated generally at 12 is provided and may be made up of damask 60 material, velour, plush or tapestry in different styles, colors, patterns and shades. In fact, the overdrape may be made of any suitable drapery material which is decorative and which is usually relatively heavy. As 65 shown in Figs. 1—3 the overdrape proper is relatively short and its upper marginal edge is stitched or otherwise suitably fastened to the upper edge of the curtain panel 10, as illustrated at 13. The overdrape 12 may be 70 provided at each side with a depending extension 14, the extensions 14 being located at the sides of the curtain and extending as far down the same as may be preferred. The extensions 14 may be formed separately from the overdrape 12 or may be formed integral 75 therewith as desired, and the upper ends only of the these extensions may be fastened or stitched to the curtain panel 10, as shown in Figs. 1 and 3, or the outer side edges of the 80 extensions 14 may also be stitched as at 15 to the main curtain panel 10, as illustrated in Fig. 4. The overdrape 12 and extensions 14 may also be connected to the curtain 10 by a second horizontal line of stitching indicated 85 at 13', if desired.

In the embodiment of the invention illustrated in Figs. 5, 6 and 7, the extensions 14 are omitted and the combined curtain and drapery simply comprises a main curtain 90 panel 16, which is similar to the curtain panel 10 shown in Figs. 1—4, and an overdrape 17 which is similar to the overdrape 12 illustrated in Figs. 1—2 and hereinabove de- 95 scribed.

As in the embodiment of the invention previously described, the upper marginal edge of the overdrape is stitched or suitably fastened to the marginal edge of the main curtain panel 16, the stitching being designated 100 at 18 in Fig. 5.

In all embodiments of the invention there is provided a curtain consisting of a main panel and an overdrape secured to the upper portion of the main panel. By providing a 105 relatively heavy overdrape whose aggregate area or size is relatively less than that of the curtain and by providing a full length light-weight curtain, the two counterbalance each other and tend to give the combined curtain 110 and drapery a graceful and pleasing hang. Moreover, the balance thus given to the hang-

ing makes it very easy to support without subjecting any of the parts thereof to undue stress or to any forces liable to impair the hang of the combined curtain or drapery or to tear or otherwise injure its parts. By forming the overdrapery of a separate piece and stitching the upper portion to the upper end of the curtain, it is permissible to use the different materials best suited to the respective purposes of the curtain and drapery. The combined curtain and drapery may be easily made up and as easily hung. Of course, any suitable means may be employed for supporting the hanging in position on the window or the like, a light curtain pole or rod and suitable curtain pins being adaptable for this purpose.

In sewing the upper edge of the overdrapery to the curtain panel, the inside of the overdrapery is laid face up with the inside of the curtain panel and the upper edges are stitched together, following which the overdrapery is folded back against the inside of the curtain panel so as to present the outside of the overdrapery to the interior of the room. This arrangement has the advantage of concealing the stitching employed to fasten the overdrapery to the curtain panel.

While I have herein shown and described several embodiments of my invention, it is 30 to be understood that various changes in size, form, construction and arrangement of the parts may be made without departing from the spirit of the invention or the scope of the subjoined claim.

I claim:

A combined curtain and drapery for application to windows having a single curtain pole thereon, comprising a curtain panel of desired width and length for covering the 40 window and being of the usual relatively light curtain material, and an overdrapery of relatively heavy decorative material of considerably less length than the curtain panel and adapted to extend across the upper end 45 of the curtain panel, the upper edge portions of the overdrapery and of the curtain panel being secured together and adapted to support the curtain from the overdrapery with the latter hanging over the curtain pole whereby 50 the respective weights of the overdrapery and the curtain panel may be substantially counter-balanced over the pole.

In testimony that I claim the foregoing as my invention, I have signed my name hereto.

JACOB AIZENMAN.
